Inventor:

A. Pritzker
By Egulan R. Cere,
Atty.

UNITED STATES PATENT OFFICE.

ASHER PRITZKER, OF TORONTO, ONTARIO, CANADA, ASSIGNOR TO THE NATIONAL ELECTRIC HEATING COMPANY, LIMITED, OF TORONTO, CANADA.

SUPPORTING BASE FOR CURRENT CONDUCTORS.

Application filed April 4, 1922. Serial No. 549,513.

To all whom it may concern:

Be it known that I, ASHER PRITZKER, of the city of Toronto, county of York, Province of Ontario, Canada, a subject of the 5 King of Great Britain, have invented certain new and useful Improvements in Supporting Bases for Current Conductors, of which the following is a specification.

My invention relates to improvements in 10 supporting bases for current-conductors, and the object of my invention is to provide a supporting base, made of any suitable insulating material, for example, porcelain, and to construct said base so that 15 the current-conductor may be suitably strung thereon quite rapidly, so as to produce various designs, and in the following specification I shall disclose my form of construction, and the manner in which the current-conductor is strung to produce a particular design, and what I claim as new will be set forth in the claims forming part of this specification.

Fig. 1 is a front elevation of my supporting base showing strung thereon the current-conductor. This view also shows my supporting base as provided with mounting means. Fig. 2 is a vertical cross-section on the line 2—2, Fig. 1.

30 In the drawings like characters of reference refer to the same parts.

My base may be used for mounting a current-conducting wire or filament, of any desired form, and for any purpose in the 35 electrical art, though in the disclosure made I use the base as a support for a resistor or heating element to be used in connection with electrical heating-and-cooking appliances.

40 A is the base, and countersunk in opposing edges thereof, are recesses D, the shape of which may vary. The formation of each of the said recesses provides a post or pin C which is laterally spaced apart from 45 the sides of said recesses by means of the open slots B which open through to the face, or front side of the base. Each post or pin C is slotted as at E at the base thereof, and in its rear side to receive the loop 50 F of the current-conducting element G'.

Upon inspecting Fig. 1, it will be observed that the current-conducting element G' is strung over the front face of the base A by means of the posts or pins C, and that this is a quick method of associating the said 55 elements.

Of course the binding posts for the current-conducting element G' may be of any desired character, and may be suitably located. H are conventional binding posts 60 preferably countersunk in the front face of the base A by means of recesses G.

I is any suitable mounting means for the base A; this mounting means may or may not be used, depending entirely upon the 65 field of use of the article.

The posts or pins C in the example of my base, are located in staggered positions in opposite edges of the base. This location of said posts will enable me to string the 70 current-conducting element G' in place and obtain the desired design.

The posts or pins C are located at one end of the recesses D adjacent the front face or side of the base A and so proportioned that the loops F will not be longer than desired. 75

Since the posts or pins C do not project beyond their associated edges of the base A, it will be understood that a number of these 80 bases may be placed one upon the other, and edge to edge, and build up, for example, a backing for various types of grates.

What I claim is:

As a new article of manufacture, a supporting base provided with a plurality of spaced recesses in opposite edges thereof extending through from one side of the base to the other to form a post or pin at one end of each recess, which posts or pins are 85 located to be flush each with its associated edge of said base and the face thereof, and each of which is narrower in width than the width of its associated recess thus spacing each post or pin at each side apart 90 from the adjacent wall of its recess, each post or pin being provided in its rear side with a slot. 95

ASHER PRITZKER.
